CLAIM

The ornamental design for a cooler for wine as shown and described.

DESCRIPTION

The patent file contains at least one drawing executed in color. Copies of this patent with color drawing(s) will be provided by the Patent and Trademark Office upon request and payment of the necessary fee.

1.1 is a top perspective view.

1.2 is a front elevation view.

1.3 is a bottom plan view.

1.4 is a top plan view.

The portions of the cooler for wine shown behind a red, translucent overlay form no part of the claimed design.
